ABSTRACT OF THE DISCLOSURE

Oxidation of α,α -dialkyl- γ -cyanobutyraldehydes to their corresponding carboxylic acids using boric or titanic acid esters as catalysts.

The present invention relates to a process for the manufacture of α,α -dialkyl- γ -cyanobutyric acids by the oxidation of aldehydes of the general formula

wherein R_1 and R_2 each represents an aliphatic radical and R_1 can be the same or different.

It is in the prior art to oxidize aldehydes with oxygen, oxygen-containing gases in an acid or neutral medium, or other oxidants such as nitric acid, to form the corresponding acids. It is not possible, however, to produce α,α -dialkyl- γ -cyanobutyric acids by the oxidation of the corresponding α,α -dialkyl- γ -cyanobutyraldehydes with nitric acid, because in this case the nitrile group is simultaneously hydrolyzed and accordingly the dicarboxylic acids are obtained (Houben-Weyl, "Methoden der organischen Chemie," vol. 8, 4th ed., p. 413). The oxidation of α,α -dialkyl- γ -cyanobutyraldehydes with oxygen in an

butyric acids by the oxidation of α,α -dialkyl- γ -cyanobutyraldehydes is carried out in an acid or neutral medium with oxygen or oxygen-containing gases as the oxidizing agents, in inert solvents and under pressure if desired. The catalysts are esters of boric acid and/or titanic acid which are preferably used in quantities of 0.1 to 10% of the weight of the aldehyde being oxidized.

The oxidation is best performed between -10 and 200°C , and preferably between 20 and 100°C . It can be done at normal pressure or at elevated pressure. Aliphatic, cycloaliphatic or aromatic hydrocarbons and carboxylic acids and their esters are suitable as solvents. Suitable exemplary solvents include benzene, toluene, xylene, hexane, heptane, cyclohexane, acetic acid, butyric acid, etc. It is preferred to employ the acid being produced as the solvent since this facilitates product recovery.

Alkyl esters having alkyl groups of up to about 6 carbon atoms are preferred for use as catalysts. These are exemplified by methyl esters, isopropyl esters and butyl esters.

The oxidation can be performed with the following α,α -lower alkyl substituted aldehydes for example:

α,α -dimethyl- γ -cyanobutyraldehyde,
 α,α -diethyl- γ -cyanobutyraldehyde,
 α -methyl- α -n-propyl- γ -cyanobutyraldehyde,
 α,α -dipropyl- γ -cyanobutyraldehyde,
 α -ethyl- α -butyl- γ -cyanobutyraldehyde,
 α -n-propyl- α -pentyl- γ -cyanobutyraldehyde,
 α,α -dipentyl- γ -cyanobutyraldehyde, or
 α,α -dihexyl- γ -cyanobutyraldehyde.

Surprisingly it has been found that, when the catalysts according to the invention are used, the transformation rates can be improved considerably over the processes known hitherto. The process also has the advantage that the α,α -dialkyl- γ -cyanobutyric acids, which are solid in the normal state, are obtained directly in crystalline form.

The process of the invention will now be further explained with the aid of examples, the results of which are summarized in the following table.

Experi- ment	Compound	Oxi- dant	Catalyst	Solvent	Pressure (atmospheres overpressure)	Oxidation Temp. ($^\circ \text{C}$)	time (in hrs.)	Transfor- mation (in percent)
1	$\text{R}_1=\text{CH}_3$, $\text{R}_2=\text{CH}_3$ — O_2	1%	$\text{B}(\text{OC}_2\text{H}_5)_3$	α,α -dimethyl- γ -cyanobutyric acid.	10	30-40	6	68.5
2	Some as above	O_2	1% $\text{Ti}(\text{OC}_2\text{H}_5)_4$	do	15-20	45-50	6	60.3
3	do	O_2	0.5% $\text{Ti}(\text{OC}_2\text{H}_5)_4$	Benzene	10	30-40	6	62.8
4	$\text{R}_1=\text{C}_2\text{H}_5$, $\text{R}_2=\text{C}_2\text{H}_5$ — O_2	0.5%	$\text{B}(\text{OC}_2\text{H}_5)_3$	n-Hexane	10	30-40	6	70.3
5	$\text{R}_1=\text{C}_2\text{H}_5$, $\text{R}_2=\text{C}_2\text{H}_5$ — O_2	2.5%	$\text{B}(\text{OC}_2\text{H}_5)_3$	do	15-20	40-50	6	58.6
6	$\text{R}_1=\text{C}_2\text{H}_5$, $\text{R}_2=\text{CH}_3$ — O_2	1%	$\text{B}(\text{OC}_2\text{H}_5)_3$	α,α -dimethyl- γ -cyanobutyric acid	10	30-40	6	66.1
7	Same as above	O_2	1% Ag_2O	do	10	30-40	6	39.2

acid or neutral medium, which is catalyzed by silver oxide and salts of silver, nickel, manganese or cobalt, and by other catalysts, does produce α,α -dialkyl- γ -cyanobutyric acids, but the transformation rates remain relatively unsatisfactory. In an alkaline medium the transformation rates improve, but in this case the disadvantage is that the acids are obtained in the form of their salts and first have to be set free by acidification.

It is therefore an object of this invention to provide a novel process for the oxidation of α,α -dialkyl- γ -cyanobutyraldehydes to their corresponding carboxylic acids.

It is another object of this invention to provide a novel catalyst for this reaction.

Other and additional objects of this invention will become apparent from a consideration of this entire specification.

In accord with and fulfilling these objects, one aspect of this invention resides in the use of boric or titanic acid esters to catalyze the oxidation of α,α -dialkyl- γ -cyanobutyraldehydes to their corresponding carboxylic acids.

This method for the production of α,α -dialkyl- γ -cyano-

The oxidation was carried out in an autoclave having a magnetic stirrer. The isolation of the reaction products is described in Examples 1, 4 and 5.

55 (1) Isolation of α,α -dimethyl- γ -cyanobutyric acid

After the oxygen oxidation is completed, the pressure in the autoclave is relieved and the autoclave is emptied into a distillation flask in which the mixture is briefly heated in a current of nitrogen and then the unreacted α,α -dimethyl- γ -cyanobutyraldehyde is removed by distillation in vacuo at 0.2 torr between 65 and 70°C . After a small amount of first runnings, α,α -dimethyl- γ -cyanobutyric acid distills out at 124 to 126°C . and 0.1 torr and hardens crystallinely in the receiver. M.P. 48°C . (from ethyl alcohol). Transformation 68.5%.

Calculated for $\text{C}_4\text{H}_11\text{NO}_2$ (mol. wt. 141) (percent): C, 59.61; H, 7.81; N, 9.94. Found (percent): C, 59.66; H, 7.96; N, 10.63.

70 (2) Isolation of α,α -diethyl- γ -cyanobutyric acid

After the absorption of oxygen ends the pressure in the autoclave is relieved, and its contents are emptied

into a distillation flask and the n-hexane is removed by distillation under normal pressure, under flowing nitrogen. The distillation is ended at a sump temperature of 90° C. Upon cooling, the α,α -diethyl- γ -cyanobutyric acid precipitates and is removed by filtration; after recrystallization from n-heptane it has a melting point of 89° C. Transformation: 70.3%

(3) Isolation of α -ethyl- α -butyl- γ -cyanobutyric acid

After the oxidation with oxygen has been completed, the pressure in the autoclave is let off and the autoclave is emptied into a distillation flask; the mixture is briefly heated under a stream of nitrogen and then fractionated. The α -ethyl- α -butyl- γ -cyanobutyric acid boils as a single fraction at 155-160° C. and 0.2 torr. Transformation: 58.6°.

Calculated for $C_{11}H_{19}O_2N$ (197) (percent): C, 66.99; H, 9.64; N, 7.11. Found (percent): C, 66.59; H, 9.35; N, 7.45.

Experiment 7 was performed under the same conditions as Experiment 6 except that silver oxide was used as the catalyst instead of the ester of boric acid.

The process of this invention can be carried out batch-wise or continuously as desired. It is possible to produce several batches of product and then to purify such 25 cumulatively.

What is claimed is:

1. In the process of producing α,α -di-lower alkyl- γ -cyanobutyric acids from their corresponding aldehydes by oxidation thereof with oxygen at a temperature of about -10 to +200° C. at normal up to elevated pressures in the presence of a catalyst and an inert solvent; the improvement which comprises utilizing as the catalyst about 0.1 to 10 weight percent, based upon the weight of the aldehyde being oxidized of at least one 35 260-404

member selected from the group consisting of boric and titanic acid esters having as the alcoholic moieties thereof alkyl group having up to about 6 carbon atoms.

2. The process claimed in claim 1 wherein said inert solvent is selected from the group consisting of hydrocarbons and carboxylic acids.

3. The process claimed in claim 1 carried out at about 20 to 100° C.

4. The process claimed in claim 1 wherein the alcohol moiety of said esters is at least one member selected from the group consisting of methyl, ethyl, propyl and butyl.

5. The process claimed in claim 1 wherein the alkyl moiety of said aldehyde reactant is at least one member selected from the group consisting of methyl, ethyl, propyl, butyl, pentyl and hexyl.

6. The process claimed in claim 2 wherein said solvent is the acid being produced.

7. The process claimed in claim 2 wherein said hydrocarbon contains no non-benzenoid unsaturation.

20 8. The process claimed in claim 2 wherein said solvent is at least one selected from the group consisting of benzene, toluene, xylene, cyclohexane, hexane, heptane, acetic acid and butyric acid.
